(57) **CLAIM**

The ornamental design for a billiards table as shown and described.

DESCRIPTION

FIG. 1 is a top perspective view of a billiards table in accordance with the present disclosure;

FIG. 2 is a front elevation view of the billiards table of FIG. 1;

FIG. 3 is a top view of the billiards table of FIG. 1;

FIG. 4 is a side elevation view of the billiards table of FIG. 1;

FIG. 5 is a magnified top perspective view of the billiards table of FIG. 1; and,

FIG. 6 is a magnified front elevation view of the billiards table of FIG. 1.

The heavy broken lines of magnified views FIG. 5 and FIG. 6 delineate the perimeter of the enlarged detail views and form no part of the claimed design; the lighter broken lines in the figures are used to represent environmental structure that forms no part of the claimed design.
